UNITED STATES PATENT OFFICE.

ISAAC B. HENDRICKSON, OF ROCHESTER, NEW YORK, ASSIGNOR TO
HENRIETTA VETTER, OF ROCHESTER, NEW YORK.

CARD-INDEX SYSTEM.

SPECIFICATION forming part of Letters Patent No. 715,799, dated December 16, 1902.

Application filed April 29, 1902. Serial No. 105,159. (No model.)

To all whom it may concern:

Be it known that I, ISAAC B. HENDRICKSON, a citizen of the United States, residing at Rochester, in the county of Monroe and State 5 of New York, have invented a new and Improved Card-Index System, of which the following is a specification.

The object of my invention is to provide a card-index system by means of which the 10 cards can be classified in two directions, one in a direction reading from the front to the rear of the drawer and the other in a direction transversely of the direction of such first-named classification, with such second classification effected by means of movable indicators, whereby any one index-card may be 15 readily changed from any one to any other classification in one or both of such directions.

20 In carrying out my invention I provide, in connection with a series of cards which have characters thereon indicating different subclasses, a series of movable indicators which may be set opposite any desired one or both 25 of such series of characters formed upon the card of such a character that they may be readily removed and placed opposite any other one of either one of such series of characters on such card and then again still later moved 30 to still further characters or to the first-mentioned characters, whereby such cards may be repeatedly used in the same classification and subclassification without the confusion which would result from the cancellation or punching 35 out of any one of such characters standing for one of such classifications or subclassifications.

By means of my system cards may be indexed in two different classifications at the 40 same time, and it is immaterial what these classifications are. One may relate to time and the other relate to alphabetical or other basis of classification. By my system I am able to make use of three systems of classification in the same tray or drawer when desired.

The accompanying drawings, illustrating my invention, are as follows:

Figure 1 is a view of one form of card adapted to use in my invention with the indicating clips or pointers used in connection there-

with. Fig. 2 is a similar view of a second form of card. Fig. 3 is a top view of a tray or drawer filled with the above cards. Figs. 4 and 5 are front and side views, respectively, 55 of one of the pointers used with my cards; and Figs. 6 and 7 are front and side views, respectively, of one of the double tab-clips used to support any desired tab upon one of the cards. 60

Similar letters refer to similar parts throughout the several views.

In carrying out my invention I prefer to make use of cards which for any given classification or system of classification are practically all alike, and upon the first one of such cards in any classification I prefer to place a double or tab clip, in the upper portion of which I locate a slip of cardboard or other similar material having a character 70 thereon standing for a classification, and of course for that classification in which are contained all the cards between this one just mentioned and the next card of a similar character but bearing a different classification character in the double clip thereon. These double clips may be preferably located at or near the left-hand upper corner of the card, as indicated in Figs. 1 and 2. If for any reason it is desired to displace this double clip and the character carried on the upper end thereof, it may be located, as indicated in Fig. 2. The purpose of these cards then is to divide the cards in the tray into classifications longitudinally of the tray. 75 These cards, as already indicated, may be exactly like any of the other cards in the classification, and they will of course carry only the character indicated beginning with each successive class throughout the drawer. 80 For that reason the cards will bear no memoranda or names of any parties calculated to constitute them regular index-cards having specific memoranda or indications thereon. 85

Referring to Figs. 1, 4, 5, 6, and 7, the card 90 *c*, which without the pointer *a* and tab *b* may be any one of a system of regular index-cards, has near its upper edge a series of figures "1" to "31," inclusive, horizontally arranged, and under these figures, as indicated, is printed 100 in a similar row the names of the months of the year, the names of the months being placed

directly below some one of the figures in the row of figures above it. This card *c* may be filled in, as indicated, with the name and address of an inquirer, the file number given 5 him, catalogue sent him, and source of inquiry, or any other data that may be useful to the business concerned. It is here assumed that the catalogues and advertising means are keyed and that *x*-13 represents the particular medium causing the inquiry and *D*⁴ the particular catalogue sent in reply, together with form letter "A" on March 10. At 10 the same time it is deemed wise, we will say, to write this same inquirer again on March 15 20, and a white or nickeled pointer *t* is placed upon "March" and a dark or blued pointer *d* is placed upon "20." On March 20 the desired letter is written and the appropriate memorandum entered in writing upon the 20 card *c* and pointers *t* and *d* are moved to the next date—say May 5—upon which it is thought wise to write another letter, such pointers then located as indicated in dotted lines in Fig. 1 at *t'* and *d'*. It will be seen that 25 an indication for a next action may be set on any day of any month for one year from the current date without the possibility of confusion. Thus it will be seen that by the use of my system the same card can be used for several 30 years in succession and that the card is never in any way mutilated or the classification indications thereon, so as to prevent the use of the card repeatedly in a recurring series for the same date of any other month or for the 35 same month of the next succeeding year. When the space for memoranda upon the card has been exhausted, another exactly similar card may be put immediately behind it and the memoranda continued thereon; 40 but pointers need not be used on such subsequent cards as any cards without pointers back of any pointer or pointers on any index-card and in front of the next pointers on a succeeding card all belong to or go with the 45 card in front of them. The pointers *t* and *d* may be used, of course, on all of the index-cards in the tray except those cards which are to be left blank and used as classification cards or those cards used for continuation of 50 memoranda, as explained.

The construction of the pointers *t* and *d*, as well as the clips *t'*, will readily be understood from Figs. 4, 5, 6, and 7. The pointer *t* has punched from its body the narrow strip *t*³, 55 which makes an opening through pointer *t* to show the indication upon which it is set and at the same time forms a spring which presses upon the back of the card and holds the pointer firmly thereon. The clip *t'* is similarly made, excepting that it has two springs *t*⁴ and *t*⁵, one on either end, one to hold the clip upon the card, the other to hold any desired tab in place. Clips *d* are similar to clips *t*, as seen, except that they are blued, while 65 clips *t* are nickeled.

In Fig. 2 is seen a modified form of card, differing somewhat from that shown in Fig. 1.

The card *c'* has near its upper edge a row of figures, "1" to "31," inclusive, and directly beneath these figures a row of letters, "A" to "Z," inclusive. A light pointer *t* is used to indicate some one particular letter, and a dark pointer *d* is used to indicate some one number. This card may be used in connection with a definite system for following up 70 inquiries, such that the letters referred to indicate the different steps of that system, the various form-letters used, catalogues, circulars, &c. The figures indicate the days of the month, and hence pointer *d* shows when 75 the next letter is to be written, and pointer *t* shows the nature of a communication sent or to be sent, as desired, thus showing how far the regular system has been used in the last letter. This card is of use in cases where a 80 large proportion of the inquiries coming in are capable of being readily handled by the same routine of correspondence and in which the next communication is to be sent within one month from the date of the last one. In using 85 the style of card shown in Fig. 2 the clip *t'*, carrying tab *b'*, may be used on one of the regular index-cards and such card left blank, as already described in reference to Fig. 1.

Fig. 3 shows a complete tray or drawer *T* of 90 cards *c* *c*, with tabs *b*, all at the upper left-hand corners, and with pointers fixed to the different cards as desired. The arrangement of the classifications shown is, first, by means of the tabs *b* an alphabetical one, which may 100 be used in the usual way, and, second, by means of the pointers, as shown in Fig. 1, a separate classification is secured in a direction at right angles to the first, such second classification being one of time. By using the 105 cards shown in Fig. 2 two cross classifications may be secured in this same direction, which would then be indicated by the pointers *t* and *d*. If the day and month to be indicated are one above the other or if the day and step in 110 the system are above one another, one pointer suffices to make the two indications.

It will be noticed that there is a row of short marks on the upper edge of the cards shown right over the figures of the upper row. These 115 marks combine, when the cards are tilted back a little away from the front of the tray or drawer *T*, to form series of lines across the tops of the cards, as seen in Fig. 3, to facilitate the selection of the cards of a certain one of 120 the subclasses across the tray or drawer.

I desire to call attention especially to the fact that while for the purpose of explaining my invention and illustrating it I have made use of the terms "classification" and "sub-classifications" the term "subclassification" does not indicate necessarily a classification of lesser importance, as the classification in point of time by months and days may be even more important, perhaps, than the classification alphabetically by means of the cards carrying the removable tabs. I desire also to call attention to another one of the very many uses to which my invention may be put—

namely, the cataloguing of a vast number of objects—such, for instance, as patents in the Patent Office into, say, divisions, classes, and subclasses. In this use of my invention each 5 card would have the name, date, number, and title of a patent written thereon. The patent might naturally be classified under two or more divisions, perhaps, as a reference. It might have received examination in some 10 instances in two or more divisions, or it might naturally fall in two or more classes and subclasses as they are now arranged. In using my invention in so cataloguing the patents the desired number of cards will be filled out alike 15 with the title, date, and number of the patent and the name of the patentee, and then the movable pointers will be put on—one to indicate the class and the other to indicate the subclass—and the cards then put into the proper 20 divisions, and the class and subclass would be indicated by the movable pointers. If at any time, as the result of a reclassification, the patent is to be transferred from one division, class, or subclass to another, this is readily 25 done by merely changing the movable pointers. The cards are not changed, but may bear permanent records, which it is not necessary to mutilate or modify in making any such changes in the classification. This use 30 of my invention would constitute, of course, only a card-catalogue of all the issued patents.

What I claim is—

1. In a card-index system, a tray containing a series of cards, such cards divided into 35 classes in one direction across the tray by means of cards carrying classification characters, the cards in each class having common characteristics and bearing characters indicating different subclassifications, such

subclassifications reading transversely of the 40 first classification, and movable pointers for indicating the subclasses upon each card.

2. In a card-index system, a drawer or tray containing a series of cards divided longitudinally of the drawer or tray into classes, such 45 classes indicated by a series of cards bearing classification characters, all the cards between any two cards carrying classification characters belonging to a single common class or division and therefore having some character 50 in common, the cards in such classes bearing also a series of characters arranged in rows transversely of the drawer or tray containing such cards, and movable pointers for indicating the characters designating the 55 different cards in each class as falling additionally in some one of several subclasses.

3. In a card-index system, a drawer or tray containing a series of cards divided longitudinally of the drawer or tray into classes, such 60 classes indicated by a series of cards bearing classification characters, all the cards between any two cards carrying classification characters belonging to a single common class or division and therefore having some character 65 in common, the cards in such classes bearing also two series of characters arranged in rows transversely of the drawer or tray containing such cards, and movable pointers having different characters for indicating the 70 characters designating the different cards in each class as falling in each of such two subclasses.

ISAAC B. HENDRICKSON.
